UNITED STATES PATENT OFFICE.

HOWARD N. JONES, OF PROVIDENCE, RHODE ISLAND, ASSIGNOR OF ONE-HALF TO
TEUNAUSKI Z. CARPENTER, OF PROVIDENCE, RHODE ISLAND.

SEPARABLE-DIE HOLDER.

Application filed May 15, 1920. Serial No. 381,764.

To all whom it may concern:

Be it known that I, HOWARD N. JONES, a citizen of the United States, residing at Providence, in the county of Providence and State of Rhode Island, have invented 5 certain new and useful Improvements in Separable-Die Holders, of which the following is a specification.

This invention relates to improvements in 10 separable die holders; and has for its object to provide means in a holder of this character for carrying two separable parts of a thread-cutting die, means also being provided in the holder whereby the halves 15 of this die may be readily separated sufficiently to disengage the work and be removed directly therefrom and then readily readjusted for another cutting operation.

It is found in practice that by providing 20 means for readily and quickly opening the die after a cutting operation it may be at once removed from the work without the slow backing-off process incident to the use of the solid die and which opening action also 25 obviates the possibility of stripping or scoring the thread in backing-off; then again by my improved construction the ordinary or standard button die may be employed which may be readily split and applied to 30 the separable parts of my improved holder.

The nature and advantages of the invention will be better understood when the following detail description is taken in connection with the accompanying drawings, 35 the invention residing in the combination and arrangement of parts as claimed.

In the drawings forming part of this specification like numerals of reference indicate similar parts in the several views and 40 wherein:—

Figure 1 is a front elevation of my improved die holder.

Figure 2 is a front elevation partly in section, of the holder.

Figure 3 is a central sectional edge view through the holder.

Figure 4 is a perspective view of the double cam-operating handle.

Figure 5 is a detail partly in section, illustrating the cam in position to act upon one of the connecting pins to lift it and its die block to operative position.

Figure 6 is a perspective view of the mov-

able die block detached and with the die removed. 55

With reference to the drawings, 10 designates the body portion of the die holder, which is provided with operating handles 11 at either end thereof. This body portion is recessed at 12 into which recess is 60 slidably mounted a die-block 13. The side faces of this body portion and of this block are each recessed as at 14 and 15 for the reception of the halves 16 and 17 of a so-called round or button die which has been 65 split or divided into two parts. Each of these die halves is held in its respective socket against rotation by means of stop pins 18 and 19.

In order to connect this die block 13 to 70 the body of the holder 10 so that it may receive a reciprocating motion therein, I have provided a pair of elongated pins 20, the inner end of each being threaded and screwed into this die block on either side 75 of the die, the outer end of each of these pins being provided with a head 21 rounded on its under surface as at 22. In order to control the movement of this die-block in the head I have provided a cam-bar 23 which 80 is pivoted at 24 between the pins 20 and is provided with oppositely-directed, inclined surfaces, each of which is adapted to engage the under side 22 of each of the pin heads when the cam-bar is swung on its 85 pivot 24 to cause these heads to slide upward on their respective inclined surfaces and move both ends of the die block simultaneously inwardly to their normal or working position. 90

In order to move this die block outwardly when released by the double cam member 23 I have provided recesses in the body portion, in which are mounted coil springs 26 to encircle the pins and act against the block 95 to normally force it outward.

The operating position of this die block may be adjusted by rotating the threaded portion of the pins 20 in the block after which the set screws 27 in the block are set 100 up against the ends of these pins to firmly lock them in adjusted position.

To positively guide this die block in its in and out movement in the body portion of the holder, I have provided guide pins 105 28 which engage grooves 29 in the opposite

ends of this block to insure the absolute matching of the die valves when the block is moved to operative position.

In operating my improved separable die holder it is only necessary to obtain an ordinary standard button die, split the same and grind off the edges as at 29, then drop one half into the body portion and the other half into the die block, swing the plates 30 over each half and lock these in position with thumb screws 31 which engage the slots 32 in the plates. The die block with its half of the die is now moved up into operating position by simply throwing the cam bar 23 into alinement with the operating handles 11.

After the die has been passed over the work to cut the thread, it is only necessary to throw the cam-handle 23 to the left which 20 instantly releases both of the pins 20 and permits the die block under action of the springs 26 to automatically open and release the work permitting the holder to be freely removed therefrom.

25 By this action it will be seen that I obviate the necessity of slowly backing off the die as is the case with solid dies; I also obviate the possibility of stripping or scoring of the thread in this backing-off operation and, therefore, much time is saved.

30 After the die has been removed from the work, owing to the fact that the parts are so widely separated the chips may be very readily removed and the die cleaned. To 35 restore the die-halves again to operating position it is only necessary to move the cam-bar into alinement with the handles which at once raise the die block with its half, and the tool is ready for another thread-cutting 40 operation.

45 My improved holder is simple and practical in construction and effective in its operation and by its use threads may be cut much quicker and more accurately than with the ordinary one-piece die.

The foregoing description is directed solely towards the construction illustrated, but I desire it to be understood that I reserve the privilege of resorting to all the mechanical changes to which the device is susceptible, the invention being defined and limited 50 only by the terms of the appended claims.

I claim:

- 55 1. A tool of the character described comprising a body member having oppositely extending handles, a die carrying portion on said member, a die block slidably mounted on said body member and adapted to be moved into co-operative relation with said die carrying portion of the body, a die block 60 operating member consisting of a bar pivoted at substantially its medial portion to said body member and extending in the same general direction as the handles of the body member and having a handle on at least one

end of said bar and adjacent thereto to be accessible to the hands of the operator while gripping the handles of the body member and extensions from said slideable die block lying on opposite sides of the pivot of said bar to be engaged and disengaged by said bar, when the latter is operated.

2. A tool of the character described comprising a body member having oppositely extending handles, a die carrying portion on said body member, a die block slidably mounted on said body member and having projections extending therefrom provided with enlarged portions, and a die block operating member consisting of a bar pivoted to said body member and having notched portions thereon adapted to be inserted between said enlargements on the projection and said body member, and a handle on at least one end of said bar extending in the same general direction as the handles of the body member and adjacent thereto to be accessible to the hands of the operator while gripping the handles of the body member.

3. A tool of the character described, comprising relatively movable die blocks, a projection extending from one of said blocks slidably through the other of said blocks and having enlarged outer end, means for moving said blocks into effective cooperative relation consisting of a movable member mounted on the other of said blocks and having a cam surface to engage under said enlarged end of said projection, whereby the blocks are drawn toward each other.

4. A tool of the character described, comprising relatively movable die blocks, a projection extending from one of said blocks, slidably through the body member and having enlarged outer ends, means for moving said blocks into effective cooperative relation consisting of a pivoted bar mounted on the other of said blocks and having a notch therein, and inclined cam surfaces adjacent the edges of the notch in the bar for engaging said projection between its enlarged end and said other block whereby said blocks are drawn toward each other into effective cooperative relation.

5. A tool of the character described, comprising relatively movable die-blocks, a projection extending from one of said blocks slidably through the other of said blocks, means normally urging the blocks to separate from effective co-operative position, an enlarged head on the end of said projection for limiting said movement, a pivoted operating member on said other block having a notch therein, cam surfaces adjacent the edges of the notch to engage said enlarged head between the latter and said other block for drawing the blocks into effective cooperative relation, said cam surfaces extending from the open edge of said notch and terminating at a point in advance of

the bottom wall of the notch, whereby the block is locked in its effective position when the enlarged head of the projection passes beyond said cam surfaces on the operating member.

6. A tool of the character described, comprising a body portion having a recess therein and handle portions at the end thereof, a block slidably mounted in said recess, pro-

10 jections extending from the block and slid- able through said body portion, comple- mental die members on said block and said body portion in cooperative relation, means for moving the block to maintain said die

15 sections in spaced or ineffective position, en- largements on the ends of said projections for limiting the movement of said block caused by said means and a bar pivotally mounted on the body member and having

20 slotted cam surfaces insertable between said enlargements on the projections and said body member for drawing the block and the die thereof into effective working relation with the die on the body member and

25 a handle on at least one end of said bar.

7. A tool of the character described, comprising a body member having a recess therein, a block slidably mounted in the recess, pins slidably mounted through the body por- 30 tion and in adjustable engagement with said block, resilient means interposed between said body member and the block and normally tending to separate the same enlargements on the outer ends of the pins having abut- 35 ting engagement with said body portion for limiting the separating movement of said block, and supplemental die sections remov-

ably mounted in opposing faces of said body member and said block, and means insertable between said enlargements and the body 40 member for drawing said block and the die thereof into effective working relation with the die in the body member, the adjustment of said pins in the block varying the effective working distance between said die sec- 45 tions.

8. In a tool of the character described, comprising a body member having a recess therein, a block slidably mounted in the re- 50 cess, a pair of pins projecting from the block and slidably extending through the body member and having enlargements on their outer ends for limiting the sliding movement of the block in one direction, comple- 55 mental die sections carried by opposing faces of said body member and block and in cooperative relation, yieldable means inter- posed between the block and body member for moving the dies out of effective working engagement, and a bar pivoted intermediate 60 its ends to the body member and at a point between said enlargements, and cam sur- faces on the bar insertable between said en- largements and said body member for draw- 65 ing the block against the pressure of said yieldable means to bring said die sections into effective working relation, and oppositely extending handle members on the body member and a handle on at least one end of said bar extending in the general direc- 70 tion of said handles, of the body member and adjacent thereto.

In testimony whereof I affix my signature.
HOWARD N. JONES.
